COSSETTE DISTRIBUTING MACHINE

Gustave J. Daley, Stockton, Calif., assignor to
 Holly Sugar Corporation, Colorado Springs,
 Colo., a corporation of New York

Application December 20, 1937, Serial No. 180,837

6 Claims. (Cl. 214—17)

This invention relates to the sugar beet industry and particularly to a machine for distributing the cossettes or sliced beets in a diffusion-cell battery such as commonly used in a beet sugar factory.

A diffusion battery of this character is made up of a row—either in straight line or circular arrangement—of a series of vertical tanks or cells into which the cossettes are poured from the top, and which must be distributed as they enter the cells in order to obtain a proper packing of the cossettes in the cells.

Heretofore this distribution has been carried out manually, and a major object of my invention is to provide a machine for mechanically performing this operation.

A further object of the invention is to provide a machine for the purpose so mounted and arranged relative to a battery of cells that the one machine may be successively used on the several cells of the battery, without any manual effort except for the operation of the machine controls.

The above and other objects I accomplish by means of such structure and relative arrangement of parts as will fully appear by a perusal of the following specification and claims.

In the drawings similar characters of reference indicate corresponding parts in the several views:

Figure 1 is a fragmentary side elevation of a cossette-cell battery, showing my distributing machine as positioned in operative relation with one cell.

Figure 2 is a transverse or end elevation of the machine as in the position in Fig. 1, with the cell and beet chute in section.

Figure 3 is a front side elevation of the machine detached from its supporting rails but with its parts in lowered position as in Fig. 2.

Figure 4 is transverse section on line 4—4 of Fig. 3 but with the parts in raised or non-operative position.

Figure 5 is a sectional plan on line 5—5 of Fig. 2.

Figure 6 is a fragmentary transverse elevation showing the operative connection between the propeller shaft and the shield.

Referring now more particularly to the characters of reference on the drawings, the cell-battery as here shown is of the straight line arrangement, and comprises the row of vertical cells or tanks 1 having horizontally movable swing-lids 2 on top. The cossette conveyor 3 extends along the row of cells to one side of and somewhat above the same, a feed chute 4 from

the conveyor overhanging the top of each cell a certain distance.

A pair of spaced horizontal I-beam rails 5 are supported by uprights 6 a certain distance above and in central symmetrical relation to the cells. These rails extend the full length of the battery and support the distributing machine, which is constructed as follows:

A horizontal carriage 7 is disposed between the rails and carries flanged rollers 8 riding on the lower flanges of the rails. One pair of rollers is secured on an axle 9 which is operatively connected in any suitable manner to a reversible electric motor 10 mounted on the frame.

Secured on and depending from the carriage is a frame 11 which includes vertical beams arranged to define a rectangular area. Supportedly this frame at the top and centrally of the area thereof is a vertical depending shaft 12 operatively connected as by a belt drive 13 to another electric motor 14 mounted on the carriage clear of the frame area.

Slidably keyed on shaft 12 for sliding movement relative thereto is another shaft 15, carrying a distributing propeller 16 on its lower end. The shaft 15 even when raised to its limit projects below the frame 11, and is guided adjacent its lower end by a bearing sleeve 17. This sleeve is supported from the frame 11 some distance above the bottom thereof by bracket arms 18 depending angularly toward the sleeve from the opposite sides of the frame. A collar 19 secured on shaft 15 at the top supports a pair of parallel horizontal bars 20 disposed on opposite sides of the shaft and which at their outer end carry depending hanger yokes 21 for a purpose which will be seen.

The shaft 15 is raised and lowered by hand, by the following means: Mounted on the frame adjacent the bottom and front thereof (said front being opposite to conveyor 3) is a shaft 22, parallel to bars 20 and carrying a crank handle 23 on one end. A brake device 24, controlled by a handle 25, is associated with shaft 22. A pair of chain sprockets 26, spaced symmetrically relative to the shaft 12 are mounted on shaft 22 and engage separate substantially endless chains 27. These chains separately pass from the inner sides of the sprockets upwardly about guide pulleys 28 mounted on frame 11 above collar 19 and then down and in substantially parallel and aligned relation with shaft 12 to and about guide pulleys 29 mounted adjacent sleeve 17. From pulleys 29, the chains pass upwardly and over guide pulleys 30 mounted on frame 11 above the

collar 19; the chains being secured on the collar. The chains then extend laterally to and about other guide pulleys 31 mounted on frame 11 at the front, and then down to the sprockets 26 5 on the front side.

To partly counterbalance the weight of the shaft 15 and associated parts, a counterweight 32 is preferably interposed in and connected in common to both chains on their front run, this 10 weight being guided by auxiliary vertical beams 11a of frame 11.

Disposed concentric with shaft 15 is a circular shield 33, substantially the diameter of the neck of a tank 1, and provided with an outer flange 34 15 adjacent the bottom to rest on the tank as shown in Fig. 2. The shield is cut away from top to bottom as shown in Figs. 2 and 5 for an arcuate extent sufficient to clear the chute 4.

Two pairs of upstanding rods 35 are mounted 20 in lugs 36 on the shield on the outside and some distance below the top thereof in spaced relation thereabout, the rods being also spaced somewhat outwardly from the shield as clearly shown in Fig. 5. Above the shield, the rods are 25 guided in sleeves 37 fixed on the frame 11. Above the sleeves, the rods of each pair are connected by cross-bars 38 arranged at right angles to bars 20. Each bar 38 carries an upstanding hook 39 in line with and always above yokes 21, 30 to be engaged thereby when shaft 15 occupies a certain position relative to the shield as will be seen. Motor 10 is started and stopped by hand, but the circuit (not shown) of motor 14 in addition to a hand switch is provided with a normally closed switch indicated at 40. This switch 35 is mounted in a box 41 fixed on the front of the frame 11 at a level adjacent the lowest level of weight 32, which of course corresponds to the highest position of shaft 15. The switch has a trip or opening member 42 projecting into the 40 path of downward movement of the weight so as to be engaged thereby and the switch opened (as shown in Fig. 4) when the shaft 15 approaches its topmost position.

In operation, the machine is first positioned 45 over the tank 1 to be filled by operation of motor 10 which drives the carriage. The handle 23 is then turned (after first releasing the 50 brake) in a direction to lower shaft 15 and shield 33. At this time, the propeller 16 is within the shield, as shown in Fig. 4, and the shield is hung suspended from the yokes 21, which are engaged with hooks 39 as shown in Fig. 6.

The shield and shaft are thus lowered as a 55 unit until the shield comes to rest on the tank and its downward movement is of course halted. Further rotation of handle 23 lowers shaft 15 into the tank. In the meantime, the weight 32 has raised, closing switch 40 ready for the starting 60 of the motor by the closing of the hand switch. When the propeller has been lowered to its limit, as determined by the engagement of collar 19 with sleeve 17 the motor 14 is started and the cossettes are admitted into the tank 65 through the corresponding chute 4. As the cossettes come in contact with the revolving propeller, they are thrown about the tank and distributed therein in an even manner. As the tank fills, the propeller is also raised (while still 70 rotating) by suitable manipulation of the handle 23 until the tank is completely filled.

A further raising of shaft 15 then withdraws 75 the propeller from the tank and places it within the shield, at which time the yokes 21 again engage hooks 39. Further raising of shaft 15

then raises the shield also, so that the entire machine is clear of the tanks and their covers, and may be moved along the row of tanks. The machine is then moved to the next tank or cell to be filled, and the above described cycle of operations is repeated.

From the foregoing description it will be readily seen that I have produced such a device as substantially fulfills the objects of the invention as set forth herein. 10

While this specification sets forth in detail the present and preferred construction of the device, still in practice such deviations from such detail may be resorted to as do not form a departure from the spirit of the invention, as defined 15 by the appended claims.

Having thus described my invention, what I claim as new and useful and desire to secure by Letters Patent is:

1. A cossette distributing machine for use with 20 a diffusion cell, said machine comprising a horizontally movable frame above the cell, a vertical driven shaft mounted on the frame in position to axially align with the cell, the lower end of the shaft being above the top of the cell, a tubular shaft slidably keyed on the driven shaft and depending therefrom, a distributing element on the lower end of the tubular shaft to pass into the cell from the top for operation, means applied to the tubular shaft to raise the same to 30 withdraw the element from the cell to a predetermined level thereabove, a band-like shield concentric with the tubular shaft and of a size to rest on the top rim of the cell, means mounting the shield in connection with the frame structure for vertical movement, opposed hanger yokes secured with the tubular shaft above the shield and hooks overhanging the yokes and secured with the shield; said hooks being positioned to be engaged by the yokes only after an upward movement of the tubular shaft sufficient to withdraw the element from the cell but before the said element has reached said predetermined level. 35

2. A cossette distributing machine for use with 40 a diffusion cell, said machine comprising a horizontally movable frame above the cell, a vertical driven shaft mounted on the frame in position to axially align with the cell, the lower end of the shaft being above the top of the cell, a tubular shaft slidably keyed on the driven shaft and depending therefrom, a distributing element on the lower end of the tubular shaft to pass into the cell from the top for operation, means applied to the tubular shaft to raise the same to withdraw the element from the cell to a predetermined level thereabove, a band-like shield concentric with the tubular shaft and of a size to rest on the top rim of the cell, a plurality of rods rigid with and projecting upwardly from the shield, guide sleeves fixed on the frame structure 45 through which said rods are slidably, the rods projecting above the sleeves, opposed hanger yokes secured with the tubular shaft above the shield, and hooks overhanging the yokes and rigid with the rods above the sleeves; said hooks 50 being positioned to be engaged by the yokes only after an upward movement of the tubular shaft sufficient to withdraw the element from the cell but before the said element has reached said predetermined level. 55

3. A cossette distributor for use with a diffusion cell, there being a fixed side-feed chute overhanging the top of the cell to deliver into the same; said distributor comprising a rotary distributing element, means to lower the element 70

into the cell from a level above the same, a vertical shield concentric with the element and adapted to rest on top of the cell and means to raise the shield to a level clear of the chute; said shield being cut away on the side adjacent the chute so as to clear the same when being lowered to a cell engaging position.

4. A cossette distributing machine for use with a diffusion cell, said machine comprising a frame disposed at a fixed level above the cell, said frame including vertical posts and horizontally spaced cross members near the lower end of the posts and above the cell, a vertical driven shaft journaled on the frame adjacent its upper end and supported against axial movement, a tubular shaft slidably keyed on the driven shaft and depending between said cross members, a distributor element on the lower end of the tubular shaft adapted to enter the cell when the tubular shaft is lowered, means to raise and lower said tubular shaft, a bearing for the tubular shaft engaging the same adjacent its lower end when said shaft is raised to its limit and supports for said bearing rigid with and depending from said cross members.

5. A structure as in claim 4, with a vertically movable shield about and concentric with the tubular shaft; the horizontal spacing of said supports being less than the width of the shield whereby the latter may project upwardly above the bearing. 5

6. A cossette distributing machine for use with a diffusion cell, said machine comprising a frame mounted above the cell, a vertical shaft positioned to axially align with the cell, means mounting the shaft for vertical movement and for rotating the same, a distributor element on the lower end of said shaft to enter the cell when said shaft is lowered, means applied to the shaft to raise and lower the same, a shield about the shaft to rest on the rim of the cell, rods rigid with and projecting upwardly from the shield, guide sleeves fixed on the frame through which the rods are slideable, the latter projecting above the sleeves and means between the rods above 15 the sleeves and the shaft to cause the rods to be lifted by upward movement of the shaft when the latter reaches a predetermined position in its upward travel. 20
